UNITED STATES PATENT OFFICE.

ALEXANDER W. GRELLE, OF LOGANSPORT, INDIANA, ASSIGNOR OF ONE-
THIRD TO HENRY C. CUSHMAN, OF SAME PLACE.

DESIGN FOR A BOX-LID HOLDER.

SPECIFICATION forming part of Design No. 31,999, dated December 19, 1899.
Application filed November 25, 1899. Serial No. 738,245. Term of patent 7 years.

To all whom it may concern:

Be it known that I, ALEXANDER W. GRELLE, a citizen of the United States, and a resident of Logansport, in the county of Cass and State 5 of Indiana, have invented and produced a new and original Design for a Box-Lid Holder, of which the following is a full, clear, and exact specification.

Reference is to be had to the accompanying 10 drawings, forming a part of this specification, in which similar characters of reference indicate corresponding parts in both the views.

Figure 1 is a perspective view of a box-lid holder, showing my design; and Fig. 2 is a side 15 elevation of the same.

The design in its entirety consists of a U-shaped clip, appearing with a middle portion A and parallel flanges B B', of which the flange B' terminates at its lower end in an extension B², bent outwardly, a rib B³ appearing on the outside of the extension, the lower 20

end of the middle portion A being beveled from the lower end in alignment with the outward bend of the extension B².

The leading feature of my design consists 25 of the U-shaped clip having one of its flanges appearing with an extension bent outwardly in its lower portion and with a rib on the outside of the extension.

Having thus fully described my invention, 30 I claim as new and desire to secure by Letters Patent—

The design for a box-lid holder, as herein shown and described.

In testimony whereof I have signed my 35 name to this specification in the presence of two subscribing witnesses.

ALEXANDER W. GRELLE.
